UNITED STATES PATENT OFFICE.

ROBERT BROWN, OF SPRINGFIELD, OHIO.

HARVESTING-MACHINE.

SPECIFICATION forming part of Letters Patent No. 315,901, dated April 14, 1885.

Application filed December 7, 1883. (No model.)

To all whom it may concern:

Be it known that I, ROBERT BROWN, a citizen of the United States, and a resident of Springfield, in the county of Clark and State 5 of Ohio, have invented certain new and useful Improvements in Harvesting-Machines, of which the following is a specification.

One of the objects of my invention is to provide a self-binding harvesting-machine having the main frame mounted upon a yoke, and pivoted to the journal-boxes of the driving-wheel axle in such manner as to be readily raised and lowered thereby, and also to be tipped or tilted on the main axle by a simple 15 lever movement.

Another object of my invention is to provide a gravitated float which will compress the grain upon the elevator and carry it up in a more satisfactory manner than with the 20 floats now in use, and also to simplify the construction of the float, so as to prevent it from being liable to get out of order.

Another object of my invention is to so construct the drums or rollers which propel the 25 endless carriers that they will not slip or move on the carrier-rolls as the carriers contract or expand by reason of atmospheric changes.

Another object of my invention is to employ a single sprocket-chain, so arranged in 30 combination with the sprocket-wheel as to drive the binding mechanism, cutter-bar, and grain-carriers.

Other objects of my invention will be more 35 fully set forth in the description of the accompanying drawings, in which—

Figure 1 is a rear elevation of the driving mechanism of my improved self-binding harvesting-machine. Fig. 2 is an enlarged rear 40 view of the harvester and elevating frames. Fig. 3 is a sectional elevation on line *y* *y*, Fig. 4. Fig. 4 is a top or plan view of Fig. 3. Fig. 5 is a grain side elevation of the harvester-frame. Fig. 6 is a detailed sectional elevation 45 of the tilting devices. Fig. 7 is a sectional elevation on line *x* *x*, Fig. 6. Fig. 8 is a front elevation of the adjusting-lever catch. Fig. 9 is an inner side elevation of the carrier-float. Fig. 10 is an enlarged detail view of the parts 50 thereof. Fig. 11 is a vertical section on line *y* *y*, Fig. 5. Fig. 12 is an inverted section on line *x* *x*, Fig. 9.

A represents the driving-wheel upon which the harvester-frame is principally mounted.

B represents the rear sill of the ordinary 55 platform-frame, which is supported at the extreme outer end by an ordinary grain-wheel.

C represents the journal-boxes of the driving-axle. They work in ways formed by the 60 segments D D', which are rigidly secured to the side sills, *b b*, at each end of the driving-axle. The top of the segments D D' are connected by a brace, *d*.

E represents a yoke the free ends of which 65 pass upon each side of the wheel A, and to which are bolted the ears *e* of the journal-boxes, as shown in Fig. 11.

In order to elevate or depress the main frame of the harvester, I hinge the yoke E to 70 the crank-rod E', which is screw-threaded and suitably journaled in bearings mounted on rail *a* and post *e*, as shown in Figs. 2 and 5.

F represents a screw collar or nut, which 75 engages with the screw-threads chased on the lower end of the crank-rod E'.

f f represent links, one end of each of which 80 is pivoted to the screw-collar F and the other end to the bracket *g*, which is rigidly secured to the yoke E.

In order to depress the frame *a b c d* vertically, the crank-rod E' is turned so as to depress the collar F, which carries down the rear end of yoke E, which fulcrums on the main axle, and by means of the links *J J* lowers the frame, which is secured to the yoke E by these links, thereby depressing the frame or carrying the sills *b* nearly to the ground. A reverse movement of the crank-rod E' will 85 raise the yoke E on the journal-boxes as a fulcrum and pull up the link *J J*, and consequently elevate or raise the frame.

It is desirable, also, to tilt the harvester-frame upon the main axle to accommodate itself to the different conditions of grain. 90 This I accomplish by the following mechanism:

G represents the tongue, which is pivoted to the frame by means of rigid brackets *G'' G'*.

G'' represents a link pivoted at one end to bracket *G'* and at the other end to the sliding box *H*, which is mounted and moves on ways *H'*, affixed to the tongue G.

H" represents a link, one end of which is pivoted to box H and the other to a pivoted lever, h, which is pivoted to the standard or bracket h', which is rigidly secured to the 5 tongue G.

I represents an adjusting-rod, with a series of notches cut in its edge, which slides through a mortise cut in bracket I', which is secured to the elevator-frame piece m.

I² represents the pin with which the notches in lever I engage to hold the frame in any desired fixed position. By lifting the lever I and pulling it backward the connecting-rod h H" draw the sliding box H forward, 15 and with it pulls link G'", conveying pressure to bracket G", which depresses the forward end of the harvester-frame, which is swiveled or pivoted upon yoke E by links J, one end of which links is pivoted to the forks of 20 yoke E, and the other end to the frame-pieces b b. This mode of connecting the main frame to the yoke E allows the rear end of the latter to be depressed to allow the frame to be lowered vertically, and it also allows the main 25 frame to be tipped or tilted by rocking on the axle of the driving-wheel.

The binding apparatus is mounted upon a bracket, J', which is secured to the posts c and to side rails, c' c".

K represents the main driving gear of the knotting and binding mechanism. The binding and knotting mechanism is not shown in the drawings, as any well-known binder may be employed.

K' represents the sprocket-wheel, journaled upon a bracket, J', on the outer face of which is a gear meshing with the driving-gear K.

K" represents a sprocket-wheel journaled upon the end of the crank-shaft, which crank-shaft is of ordinary construction, used to drive 40 the cutter-bar.

L represents the main driving sprocket-wheel, which is driven by the ordinary bevel-pinion, which is in turn driven by the driving-wheel A. These parts are of the ordinary 45 construction, and are not shown.

L' represents an idler-roll journaled upon the frame B.

L" represents a sprocket-wheel which is 50 fastened upon the end of the carrier-roller of the platform. This endless platform-carrier is of the ordinary form of construction. It may be either canvas or chain, as desired.

M represents a sprocket-wheel which is journaled upon a stud, M', which is rigidly secured, to one of the side pieces, m, of the elevator-frame.

m' represents a gear-wheel keyed upon the stud M', to drive the pinion n, which is keyed 60 upon the end of the endless-carrier shaft N of the floating frame O.

N' represents a sprocket-wheel keyed upon the outer end of the roller P of the elevating-frame.

65 Q represents the endless sprocket-chain, which is driven by the sprocket L, keyed upon a main shaft, and passes in the direction of the

arrows over sprocket L", which drives the horizontal platform-carrier; thence over the sprocket M, which, by means of the spur-gears m' n, drives the endless carrier of the float; thence over the sprocket N', which drives the endless carrier of the elevator-frame; thence over the sprocket K' driving the binder mechanism; thence over K", which drives the cutter-bar. 70 75

The elevating-carriers are constructed as follows: m represents the side pieces of the elevator, which are rigidly secured at one end to the binder-frame and the other to the platform-frame B. p p represents side guard-strips, 80 which are connected by transverse cross-strips p' p'. R represents the canvas carrier or endless belt, which passes around the driving-roller P' at one end, which is suitably journaled to the frame-pieces m and upon which roller is keyed the sprocket-wheel N'. A similar carrier-roller is mounted loosely, and serves as an idler at the lower end of the frame M, and an endless carrier of canvas is preferably connected around these rollers and provided 85 with the ordinary cross-strips or other means for elevating the grain. This elevator-frame and endless carrier are of the ordinary construction. I employ a gravitated float-elevator, which is formed of two pieces, as shown in 90 Figs. 1, 2, 9, 12. It has similar guards p p, and strips p' p', as shown and described for the carrier, and a similar endless belt, p³, which is driven by shaft N, as before described. A similar shaft, P', is journaled in the upper end 95 of the frame O.

In order to have the float rise under the pressure of the grain, and yet rest upon it and compress it, so as to be delivered in a compact mass to the binder-table, I mount this float so as to

105

automatically fall by gravity and press upon the grain and to be raised or lifted off from the elevator-frame by the upward pressure of the grain and elevator. I accomplish this by connecting the floating frame to the elevator-frame by parallel links S S, placed upon each side at the lower end, the upper end being held from lateral movement by guides t. This upper end may be raised independently of the lower end, and vice versa. These frame-pieces 110 O O m m of the elevator and float frames are connected somewhat after the manner of a parallel rule. The elevator-frame, being rigidly connected to the platform, is immovable, and the floating frame is allowed to rise freely by 115 the pressure, as before described, moving on the links S, and as soon as released from the pressure of the grain at either end it will automatically fall down upon the carrier-frame m. I have found by experience this mode of construction of the floating frame to be very important, and to operate in a better manner than any other form of float in ordinary use. 120 125

Great difficulty has been experienced in the use of canvas carriers. Being made of fabric 130 the moisture of the atmosphere causes them to contract, which often causes them to rip or tear, and when dry they expand and slip. These fabric carriers have caused great trou-

ble in the use of harvesting-machines, owing to this change of atmosphere. I have found by experience that the difficulties caused by the contraction and expansion of these endless carriers may be chiefly avoided by the following instrumentality: T represents rubber collars or sleeves, one or more of which may be used, and are tightly secured to the driving-shaft of the float, carrier, and elevator, respectively, and form the bearing-surfaces over which the canvas is stretched and by means of which it is propelled. The elasticity of these rolls compensates in some degree for the contraction and expansion of the fabric, and the elastic character of the rubber causes a better frictional contact of the endless belt, and prevents to a material extent the slipping of the canvas upon the driving-rollers.

t represents a side guide on the elevator-frame piece m, for preventing lateral movement of the floating frame.

I claim—

1. In combination with the main harvester-frame, a yoke, E, hinged to the boxing of the axle at one end, and to the screw-threaded collar F at the other end, working on threaded shaft E', said yoke connected to the main frame by the links J, substantially as described.
2. In combination with the harvester-frame secured to the drive-wheel axle by the yoke E, the segmental standards D D', screw-threaded shaft E', screw-collar F, and links J f, pivoted to the yoke and the frame, substantially as described.
3. In combination with the main frame A, suspended upon the main drive-wheel axle,

the tilting mechanism I h H" G'', connected to the forward end of the main frame and to the tongue G, whereby the frame may be tilted upon the main axle, substantially as described.

4. The combination, with the tongue G, the adjustable sliding box H, attached to and moving on ways H', mounted on the tongue, the link H'', connected with said sliding box, the lever h, connected with the link H'' and fulcrumed upon the tongue, and the rod I, connected with the lever h, substantially as described.

5. The combination, with the driving-wheel K, of the knotting mechanism and the sprocket-wheels K', K'', and L, mounted on the main frame, of the sprocket-wheel L'', mounted on the platform, and the sprocket-wheels M N, on the elevated carrier-frame, and the single chain Q, adapted to drive the knotting mechanism simultaneously with the raking and elevating apparatus, substantially as described.

6. In combination with the stationary carrier-frame m, having the endless apron driven by the chain Q, the gravitating float-frame O, connected to carrier-frame m by parallel hinges S, and the endless apron driven by transmitters m' n, substantially as described.

7. In combination with the driving-rollers of an endless carrier, the elastic rubber bearing-surfaces T, and endless canvas carrier working thereon, substantially as specified.

In testimony whereof I have hereunto set my hand.

ROBERT BROWN.
